UNITED STATES PATENT OFFICE

2,545,336

COMBINATION STROLLER AND SHOPPING CARRIER

Robert S. Binder, Philadelphia, Pa.

Application December 28, 1946, Serial No. 718,933

2 Claims. (Cl. 280—36)

1

My invention relates to children's strollers and particularly to a combination stroller and shopping carrier.

Hitherto, it has been difficult for women accompanied by a small child to engage in shopping, since they have had to lead the child while carrying an armload of packages. Frequently, too, the child becomes impatient with long standing and wanders off, necessitating additional searching or vigilance.

It is an object of my invention to provide a wheeled conveyance which will carry a child and a load of packages, simultaneously relieving the shopper of both burdens.

It is a further object of my invention to provide a conveyance of the type described which is collapsible and which may be stored in a small space, such as a closet, when not being used.

Another object of my invention is to provide a conveyance of the above description which can be used singly as a stroller or as a shopping carrier, the unused portion of the vehicle being collapsed so as to present no obstruction to the desired function.

Another object of my invention is to provide a conveyance of the above description, which when fully collapsed, may be used by children as a toy wagon.

Fig. 1 is a perspective view of my invention, completely assembled.

Fig. 2 is a perspective view of my invention, knocked down for storage.

Fig. 3 is a side section of my invention, as shown in Fig. 1.

Fig. 4 is a fragmentary view of the seat back showing in dotted lines, the operation of the carrier compartment lock.

Fig. 5 is a fragmentary side view of one end of the pushing rail.

Fig. 6 is a fragmentary section view showing the shock-absorbers used with the seat.

Fig. 7 is a fragmentary side section of the front end of the carriage.

Referring now to the drawings, wherein similar reference characters designate similar parts, I show a conveyance comprising a horizontal carriage A and an upright seat portion B.

The carriage A consists of a box-like structure 10, the front end of which, 12, may be rounded, for sake of appearance. Wheels 14 are secured to the sides of the structure 10 near its rear corners, and a pair of casters 16 are attached to its underside near the front for easy steering. The pushing handle is a U-shaped tube 18, whose ends 18A are secured to the sides of the structure 10

just ahead of the rear wheel by bolts 19 and are further collapsibly secured by the mechanism shown in detail in Figs. 1 and 5. A steel cable 20 passes within the legs 18A of the pushing rail 18, emerging near the cross-portion 18B and extending parallel thereto. The ends of the cable 20A are secured to the top end of fingers 22 which slide within the rail 18 and project through rearwardly-extending slots in the rail walls. The lower ends of the fingers 22 are connected by tension springs 24 to the bolts 19 previously mentioned. A rod 26 extends through the side walls; and its ends normally engage the projections of fingers 22, as shown in Fig. 5. To collapse the rail, the cable is grasped near the cross-portion of the rail, 18B, whereupon the fingers 22 disengage from the ends of rod 26 and the rail may then be rocked forward to the closed position shown in Fig. 2.

20 The snaps 28 on both sides of structure 10 serve to hold the rail in the collapsed position.

The upright seat portion B consists of a hollow back member 30, which has an angle edge 32. The back is pivotally supported upon a rod 31 which extends between the side walls of member 10, at the rear, and further, by the handlike members 34, on both sides, the finger portions of which ride upon bolts 19. While the back 30 folds into the carriage A, its top edge 30A overlaps the front of the carriage, sections 30B being cut out for that purpose. The snap-lock 36 on the carriage front in cooperation with the slot 36A serves to lock the back 30 in collapsed position, as shown in Fig. 2.

35 The seat 37 is pivotally secured to the back 30 by rod 38 which extends through the rolled seat edge 37A and into the angle edges of the sides of the seat back. The front of the seat 37 is pivotally supported by a U-shaped rod 40 whose ends 40A are further bent to fit into shock-absorber spring compartments 42 on the inner sides of the carriage. A drop panel 44 is hinged at its top to the front of the seat 37 and its bottom is connected to the ends of a U-shaped rod 46 which pivotally secures the handlike member 34 to the seat back 30. A strong tension spring 48 connects the midpoints of rods 40 and 31 and serves to automatically erect the seat from the closed position when the snap-lock 36 is released. Armrests 50 are pivotally attached to the angle edges of the sides of the back 30, their other ends being linked to the cross-portion of the rod 40 by the pivotal links 52. A safety belt (not shown) may extend between the forward ends of the armrests 50. When the seat portion of the vehicle

is collapsed into the carriage A, the drop panel 44 is folded under the seat 37 by the ends of rod 46, and spring 48 becomes stretched. A pair of wing-like doors 54 are attached to the back of member 30 by spring hinges 56 which tend to keep the doors open. A piece of fabric 58 is attached to the edges 60 of the doors and also to the back 30 so as to form a compartment or bag when the doors are open. This compartment is used to hold the packages or shopping purchases. When the compartment is empty it may be collapsed by folding the doors inwardly and securing them by the catch shown in Fig. 4. The catch consists of a pair of vertical levers 64 and 66 joined by a link 70, which is pivoted at its mid-point to the back of member 30. A clamping handle 72 is attached to the upper end of lever 64 and projects through the angle edge rim of member 30. The lower end of lever 66 carries a clamping finger 74. Members 72 and 74 engage the top and bottom edges of the doors 56 simultaneously when the handle 72 is depressed and serves to lock the wing doors in their closed position.

It is seen that the conveyance may be collapsed partially so as to serve either as a shopping carrier or as a child's stroller. Also, when the conveyance is completely collapsed, as in Fig. 2, it can still serve as a child's toy wagon, with a cord (not shown) tied to the rail 18.

Although my invention has been described in considerable detail, such description is intended as being illustrative rather than limiting, since the invention may be variously embodied, and the scope of the invention is to be determined as claimed.

I claim as my invention:

1. A combination child's stroller and shopping carrier comprising an open carriage having ground wheels thereon, a collapsible seat structure having a back, and being supported upon and foldable within said carriage, means for automatically extending said seat structure upright from the folded position, means for locking said

seat structure in the folded position, means for absorbing the shocks transmitted to said seat structure, and slideable means for varying the angle of the back of said seat structure, a collapsible shopping carrier supported upon the back of said seat structure, means for locking said shopping carrier when collapsed within the back of said seat structure, automatic means for extending said shopping carrier when unlocked, a collapsible pushing rail attached to said carriage, and means for fastening said pushing rail to said carriage when collapsed.

2. A combination child's stroller and shopping carrier comprising an open carriage having ground wheels thereon, a collapsible seat structure having a back, and being supported upon and foldable within said carriage, means for automatically extending said seat structure upright from the folded position, and slideable means for varying the angle of the back of said seat structure, a collapsible shopping carrier supported upon the back of said seat structure, means for locking said shopping carrier when collapsed within the back of said seat structure, automatic means for extending said shopping carrier when unlocked, a pushing rail attached to said carriage, and means for fastening said pushing rail to said carriage when collapsed.

ROBERT S. BINDER.
